UNITED STATES PATENT OFFICE.

CHARLES ROBERT HUGHES, OF UTICA, NEW YORK, ASSIGNOR TO UNION SPECIAL MACHINE COMPANY, OF CHICAGO, ILLINOIS, A CORPORATION OF ILLINOIS.

CONCEALED-STITCH BINDING MACHINE.

Application filed February 28, 1921. Serial No. 448,424.

To all whom it may concern:

Be it known that I, CHARLES R. HUGHES, a citizen of the United States, residing at Utica, in the county of Oneida, State of New York, have invented certain new and useful Improvements in Concealed-Stitch Binding Machines, of which the following is a description, reference being had to the accompanying drawing and to the figures of reference marked thereon.

The invention relates to new and useful improvements in sewing machines and more particularly to a sewing machine for attaching a binding to a body garment by means of stitches which are concealed from view at the right or face side of the garment.

An object of the invention is to provide a machine of the above character with a folder having means for guiding a binding strip to the needle in a plane at right angles to the line of feed and for reversing the strip and for infolding the upper edge thereof about the path of the needle and then directing the infolded edge across the path of the needle so that the needle will penetrate the inturned upper edge portion of the strip, whereby the stitching thread is concealed from view by the upper body portion of said binding strip at the right or face side of the garment.

A further object of the invention is to provide a folder for a sewing machine of the above type which is provided with means for folding the lower edge portion of the binding strip outwardly before it is reversed, so that when reversed the lower portion of the binding strip will have its edge portion inturned.

These and other objects will in part be obvious and will in part be hereinafter more fully disclosed.

In the drawings—

Figure 1 is a view from the left-hand end of a machine embodying my improvements;

Figure 2 is a top plan view of my improved folder;

Figure 3 is a front view of the folder;

Figure 4 is a rear view of the folder;

Figure 5 is a perspective view of the folder looking from a point in rear of the folder, as applied to the machine;

Figure 6 is a sectional view on the line 6—6 of Figure 2; also showing at one side of the folder the binding strip;

Figure 7 is a sectional view on the line 7—7 of Figure 2; also showing at one side of the folder the binding strip;

Figure 8 is a sectional view on the line 8—8 of Figure 2; also showing at one side of the folder the binding strip;

Figure 9 is a sectional view on the line 9—9 of Figure 6;

Figure 10 is a perspective view showing the binding and body fabric and the direction of movement of the binding strip for placing the same about the edge of the body fabric;

Figure 11 is a view on the line 10—10 of Figure 10, but showing in addition to the binding a section of the folder and also the needle;

Figure 12 is a top plan view showing a slightly modified form of folder wherein the under edge of the binding strip is flat and not inturned;

Figure 13 is a sectional view on the line 13—13 of Figure 12;

Figure 14 is a sectional view through the body fabric having the binding applied thereto by the folders shown in Figures 12 and 13;

Figure 15 is a side view of the presser foot; and

Figure 16 is a plan view of the presser foot and showing the presser bar in section.

The invention from its broadest aspect is directed to a machine having a needle disposed in a line at an obtuse angle to the plane of the work support so as to facilitate the folding of the edge of the binding strip about the path of the needle and the directing of the inturned portion of the binding strip across the path of the needle to form concealed stitches.

A machine of this general type is shown and described in the application of Robert R. Hughes, Jr., Serial No. 310,073, filed July 11, 1919, and the present invention is an improvement upon the machine shown in said application. The invention resides particularly in the folder and the manner of supporting the same and its relation to the needle. The folder is provided with means for guiding a binding strip in a line at right angles to the line of feed and for reversing said strip and folding the edge portion of the strip about the path of the needle after it has been reversed and directing the infolded portion across the path of the needle.

From certain aspects of the invention, the folder is also provided with means for folding the lowermost portion of the binding strip outwardly before it is reversed so that 5 when the strip is reversed said edge portion will be inturned. Then again, the invention from certain aspects, includes the mounting of the folder so that it may be tilted forward and back or laterally to properly 10 position the folding scroll for infolding the upper edge portion of the binding relative to the needle path.

Referring more in detail to the drawings, I have shown my invention as applied to a 15 sewing machine having a bed 1, carrying a work support 2 and a standard 3, having an overhanging arm which carries a bracket 4, in which reciprocates a needle bar 5, carrying a needle 6. The needle bar is set so as 20 to reciprocate in a line forming an obtuse angle to the plane of the work support. Said bed 1 is mounted on an inclined support 7, so that the work support 2 inclines upwardly from front to rear. Mounted on 25 the work support 2 is a folder which includes a supporting bracket 8 and a binding strip guiding and folding device 9. The support 8 is secured to the work support by means of two screws 10-10 which pass 30 through a retaining plate 11 and through an elongated slot in the support 8. There are also four screws 12 passing through the support 8 and each of these screws is provided with a cone-shaped point 13 and a lock nut 35 14. Each screw has a slot for a screw-driver so that it may be adjusted and then held in an adjusted position by the lock nut. It will readily be seen that by the manipulation of these screws 12, the folder may be tilted in 40 any direction back and forth or laterally, as desired, and the purpose of this particular manner of supporting the folder will be hereinafter more fully described.

The folder proper, for guiding and folding the binding strip, is carried by an inclined supporting plate 15, which is integral with a horizontal supporting plate 16 and this horizontal supporting plate 16 is secured to the support 8 by means of screws 50 17. As clearly shown in Figure 1, these supporting plates 15 and 16 are secured to the machine so that the plate 16 is substantially horizontal. The main body fabric is indicated at F and said main body fabric is led 55 over the plate 16, thence down the inclined plate 15 and underneath the presser foot 18. The inclined plate 15 is substantially parallel with the path of the needle 6, which is inclined to the plane of the work support, 60 as clearly shown in Figure 1. By setting the machine on the inclined support 7, the fabric is led in a substantially horizontal plane, then downwardly in a plane substantially parallel with the needle path and then under the presser foot, and it is while the fab-

ric is passing along substantially parallel with the needle path that the binding strip is applied thereto, as will be described more fully hereinafter.

The presser foot is shown in detail in Figures 15 and 16, and includes a main-section 19 carried by a presser bar 20. At the forward end of the section 19 there is an arm 21 which projects laterally in front of the auxiliary section 22 of the presser foot. Said auxiliary section 22 is carried by a post 23 which is freely slideable in the main section 19 and is yieldingly pressed downwardly by means of a spring 24. The left-hand end of the arm 21 is provided with a forwardly extending curved guiding portion 25.

The folder proper is provided with a guiding portion 26 which receives the binding and said guiding portion is slotted at 27 to receive a tool for assisting in the insertion of the binding strip. Said guiding portion 26 is formed with inner and outer walls 28 and 29, as shown in Figures 6, 7 and 8, are gradually curved so as to centrally fold the binding strip intermediate its edges as it passes through this portion of the folder. In Figure 6 of the drawings, I have shown the binding strip at B, and it will be noted that at the receiving end and adjacent thereto the binding is flat. The inner wall 28 is provided with a curved portion 30 which extends about the adjacent edge of the wall 29 for the purpose of turning the lower edge of the binding strip outwardly as it is centrally folded intermediate its edge portions. In Figure 7, I have shown at b the edge as it begins to fold outwardly. In Figure 8 this edge portion b is shown as well bent back upon the body portion of the binding strip, so that the binding strip as it passes through the guiding portion 26 will be centrally folded between its edge portions and the lower edge portion thereof only will be folded outwardly upon the body portion of the binding.

Carried by this guiding portion 26 is a scroll 31. The end of the guiding portion 26 is cut at an incline of substantially forty-five degrees to the longitudinal axis of said portion 26 and the binding strip after it leaves the end of the guiding portion 26 is reversed or inverted and led through the scroll 31. This reversing of the binding strip is accomplished after the well known fashion of an English binder.

It will be apparent, of course, that the lower folded edge portion b of the binding strip which is turned outwardly by the guiding portion 26 will, when reversed, be infolded, as clearly shown in Figure 10. After the binding strip leaves the guiding portion 26 and is reversed, it passes through the scroll 31. This scroll encircles the needle and folds the upper edge portion of

the binding strip about the path of the needle. The scroll also receives the edge of the body fabric and as a consequence places the binding strip about the edge of the body fabric. In Figure 11, I have shown on an enlarged scale the relation of the scroll of the folder to the body fabric, the binding strip and the path of the needle. In this figure the inclined plate 15 is, of course, shown as at the right of the body fabric which passes down along said inclined plate. The scroll is formed by curving the plate 15, as shown in Figure 9, where this plate 15 is indicated as being curved at 32 and ending in an inturned portion 33. Said scroll is soldered or otherwise secured to the guiding portion 26, and this guiding portion 26 is also soldered or otherwise secured to the inclined plate 15. The inclined plate 15 is provided with a slot 34 which permits the under edge portion of the binding to pass through the plate 15 to the scroll. The body fabric F extends well into the scroll and the binding, as has been noted, is placed about the edge of the body fabric.

As clearly shown in Figure 11, the needle 6 passes through the scroll and the binding is folded about the path of the needle. The body fabric also passes through the scroll and while therein moves in a direction substantially parallel with the needle. As the binding and body fabric leaves the scroll they pass underneath the presser foot of the machine, and, in order to accomplish this, they are turned into a plane at an obtuse angle to their path of travel in the scroll and fed across the needle path, so that the needle penetrates the inturned portion of the binding strip, then the body fabric and then the lower portion of the binding strip. As a result, the needle thread is laid between the upper inturned portion of the binding strip at the outer or upper face of the body fabric and the binding strip itself, and thus the thread is concealed by the upper face portion of the binding strip. This line of stitching, as clearly shown in Figure 10, is very close to the fold in the upper edge portion of the binding strip and this holds the binding tightly about the edge of the body fabric. The stitches are indicated diagrammatically at 8 in the drawings.

Inasmuch as the needle must be free from engagement with the binding strip until the point desired for penetration is reached, it is essential that the folder shall be set so that the needle will be central of the scroll, or substantially so. This may be readily accomplished by manipulating the threaded screws 12 which will tilt the folder forward or back, or to the right or to the left, as desired. In other words, these screws, together with the main clamping screws, pro-

vide a universal adjustment for setting the folder so that it may be moved in any direction to bring about its proper relation to the needle. As the binding strip and body fabric leave the folder they pass underneath the presser foot and the curved portion 25 of the foot engaging the binding strip at the fold, aids in retaining the strip from spreading at the time the needle is penetrating the infolded edge portion 75 thereof.

In Figures 12 and 13, I have shown a slightly modified form of folder whereby the lower face portion of the binding strip will remain flat and unfolded as it is stitched 80 to the body fabric. In Figure 14, the body fabric is indicated at F and the lower face portion of the binding strip is indicated at b'.

As clearly shown in Figures 12 and 85 13, the guiding portion merely folds the binding strip centrally between its edges and the lower edge is not out-turned or folded, as is done in the other form of folder described. Therefore when the binding strip is reversed or inverted, the lower face portion will be flat and unfolded. Like letters of reference have been applied to this form of folder, as, otherwise, it is similar in all respects to the folder shown 95 in Figures 2 to 9 inclusive.

From the above, it will be apparent that I have provided a machine for binding a body fabric, wherein the binding is secured by stitches which are concealed from view 100 at the front or right side of the body garment. Furthermore, the binding is guided in a direction at right angles to the line of feed and is then reversed and led along the needle path to the stitching point. This 105 enables the body fabric to be crowded well into the folder which, of course, causes the binding to be filled with the body fabric. This is especially desirable in stitching collarettes to garments.

In one form of the invention the under face portion of the binding strip is infolded and this is accomplished by outfolding or turning out the edge portion of the binding strip before it is reversed and then when it 115 is reversed said outturned portion will be inturned and the other edge portion of the binding strip is inturned and folded about the path of the needle after it is reversed. In the other form of the invention the under 120 face portion of the binding strip is not inturned and it lies flat when secured to the body fabric.

The curved section 25 on the presser foot bears against the binding strip as it leaves 125 the scroll, and, therefore, serves as a guide for the binding strip and tends to prevent said binding strip from creeping or expanding laterally.

It is obvious that minor changes in the 130

details of construction may be made without departing from the spirit of the invention as set forth in the appended claims.

Having thus described my invention, 5 what I claim as new and desire to secure by Letters Patent, is:

1. In a sewing machine, the combination of a work support, a feeding mechanism, a needle arranged to reciprocate in a line at 10 an obtuse angle to the work support, and a folder for guiding a binding strip to said needle in a line at right angles to the line of feed and for folding said strip between its edges, said folder having means for reversing the strip and for infolding the 15 upper edge portion thereof about the path of reciprocation of the needle and for directing the inturned portion of the strip across the path of the needle.
2. In a sewing machine, the combination of a work support, a feeding mechanism, a needle arranged to reciprocate in a line at an obtuse angle to the work support, and a folder for guiding a binding strip to said 20 needle in a line at right angles to the line of feed and for folding said strip between its edges, said folder having means for reversing the strip and for infolding the upper edge portion thereof about the path 25 of reciprocation of the needle and for directing the inturned portion of the strip across the path of the needle, said folder also having means for outturning the lower edge portion of the binding before it is reversed, 30 whereby said binding when reversed will have the lower edge portion thereof in-turned.
3. In a sewing machine, the combination of a work support, a feeding mechanism, a 35 needle arranged to reciprocate in a line at an obtuse angle to the work support, and a folder for guiding a binding strip to said needle in a line at right angles to the line of feed, said folder having a guiding portion 40 for receiving the binding strip and for folding the binding strip intermediate its edge portions, said guiding portion at the delivery end thereof being cut at an angle for permitting the reversing of the binding 45 strip, and a folding scroll for receiving the reversed binding strip and for infolding the upper edge portion thereof about the path 50 of reciprocation of the needle and for directing the inturned portion across the needle path.
4. In a sewing machine, the combination of a work support, a feeding mechanism, a needle arranged to reciprocate in a line at an obtuse angle to the work support, and a 55 folder for guiding a binding strip to said needle in a line at right angles to the line of feed, said folder having a guiding portion for receiving the binding strip and for folding the binding strip intermediate its edge 60 portions, said guiding portion at the de-

livery end thereof being cut at an angle for permitting the reversing of the binding strip, a folding scroll for receiving the reversed binding strip and for infolding the upper edge portion thereof about the path 70 of reciprocation of the needle and for directing the inturned portion across the needle path, and a supporting plate leading into said folding scroll for directing the edge of a body fabric through the scroll, 75 whereby the binding as it passes through the folding scroll is placed about the edges of the body fabric.

5. In a sewing machine, the combination of a work support, a feeding mechanism, a 80 needle arranged to reciprocate in a line at an obtuse angle to the work support, and a folder for guiding a binding strip to said needle in a line at right angles to the line of feed, said folder having a guiding portion for receiving the binding strip and for folding the binding strip intermediate its edge portions, said guiding portion at the delivery end thereof being cut at an angle 85 for permitting the reversing of the binding strip, a folding scroll for receiving the reversed binding strip and for infolding the upper edge portion thereof about the path of reciprocation of the needle and for directing the inturned portion across the 90 needle path, said guiding portion of the folder being provided with means for outturning the lower edge portion of the binding strip before said strip is reversed.

6. In a sewing machine, the combination of a work support, a feeding mechanism, a needle arranged to reciprocate in a line at an obtuse angle to the work support, and a folder for guiding a binding strip to said needle, said folder including a guiding portion 100 arranged at right angles to the line of feed and shaped so as to fold the binding strip between its edges, said guiding portion at the delivery end thereof being formed on an angle of forty-five degrees to 105 the line of feed so as to reverse the binding strip, a folding scroll for receiving the strip after it is reversed, said folding scroll having a curved portion extending around the path of the needle for folding the upper 110 edge portion of the binding strip about the path of the needle, and a plate extending laterally from said curved scroll for directing a body fabric into the scroll.

7. In a sewing machine, the combination of a work support, a feeding mechanism, a needle arranged to reciprocate in a line at an obtuse angle to the work support, a folder for guiding a binding strip to said needle, said folder including a guiding portion 120 arranged at right angles to the line of feed and shaped so as to fold the binding strip between its edges, said guiding portion at the delivery end thereof being formed on an angle of forty-five degrees 125 to the line of feed so as to reverse the binding strip, a folding scroll for receiving the strip after it is reversed, said folding scroll having a curved portion extending around the path of the needle for folding the upper edge portion of the binding strip about the path of the needle, and a plate extending laterally from said curved scroll for directing a body fabric into the scroll.

to the line of feed so as to reverse the binding strip, a folding scroll for receiving the strip after it is reversed, said folding scroll having a curved portion extending around the path of the needle for folding the upper edge portion of the binding strip about the path of the needle, and a plate extending laterally from said curved scroll for directing a body fabric into the scroll, said guiding portion being provided with means for overturning the lower edge portion of the binding strip before said strip is reversed.

8. In a sewing machine, the combination of a work support, a feeding mechanism, a needle arranged to reciprocate in a line at an obtuse angle to the work support, a folder for receiving and folding and reversing a binding strip and having means for infolding the upper edge portion of the binding strip about the path of the needle and for directing the inturned portion of the strip across the path of the needle, a support for said folder, and means for attaching said support to the work support of the machine whereby said folder may be adjusted forward and back and laterally for centering the needle in the means for folding the upper edge portion of the binding strip.

9. In a sewing machine, the combination of a work support, a feeding mechanism, a needle arranged to reciprocate in a line at an obtuse angle to the work support, a folder for receiving and guiding and reversing a binding strip and having means for folding the upper edge portion of the binding strip about the path of the needle and directing the inturned portion of the strip across the path of the needle, a support for said folder, clamping screws for securing the support for the folder to the work support of the machine, and a plurality of positioning screws extending through the folder support and bearing against the work support for tilting the folder forward and back and laterally.

10. In a sewing machine, the combination

of a work support, means on which said work support is mounted, so that the work support inclines forward from front to rear, a feeding mechanism, a needle arranged to reciprocate in a line at an obtuse angle to the work support, a folder for guiding a binding strip to said needle, a horizontal supporting plate over which the body fabric is directed, an inclined supporting plate carried thereby, and substantially parallel with the path of the needle, said folder being mounted on said inclined supporting plate and having a folding scroll extending about the path of the needle.

11. In a sewing machine, the combination of a work support, means on which said work support is mounted, so that the work support inclines forward from front to rear, a feeding mechanism, a needle arranged to reciprocate in a line at an obtuse angle to the work support, a folder for guiding a binding strip to said needle, a horizontal supporting plate over which the body fabric is directed, an inclined supporting plate carried thereby, and substantially parallel with the path of the needle, said folder being mounted on said inclined supporting plate and having a folding scroll extending about the path of the needle, said folding scroll being formed as a part of the inclined plate.

12. In a sewing machine, the combination of a work support, a presser foot, feeding mechanism, a needle arranged to reciprocate in a line at an obtuse angle to the work support, a folder for receiving and guiding and reversing a binding strip and having means for folding the upper edge portion of the binding strip about the path of the needle and directing the inturned portion of the strip across the path of the needle, said presser foot having a curved portion disposed so as to bear against the binding strip as it leaves the folder for preventing the binding strip from creeping or expanding laterally.

In testimony whereof, I affix my signature.

CHARLES ROBERT HUGHES.
